UNITED STATES PATENT OFFICE.

GERALD R. LIVERGOOD, OF HOUSTON, TEXAS, ASSIGNOR OF ONE-FOURTH TO W. L. PEARSON, OF HARRIS COUNTY, TEXAS.

DETACHABLE PILOT FOR PUMP PLUNGERS.

Application filed June 25, 1926, Serial No. 118,511. Renewed June 26, 1928.

My invention relates to a pilot for use on a pump plunger in deep well pumping. It is particularly adapted for use in reciprocating pumps of the type of pump ordinarily termed a "packed pump", in which the packing between the pump barrel and the piston is mounted on the pump barrel itself.

In the packing ordinarily employed in deep well pumping to pack off the space between the plunger and the pump barrel, said packing is expanded against the plunger during the operation of the pump, and when it becomes necessary to withdraw the plunger from the well, as sometimes occurs, the packing about the plunger will expand inwardly after the plunger is removed, partially filling the space occupied by the plunger. When it is desired thereafter to insert the plunger back into the pump barrel, the packing has so filled the interior of the barrel that the plunger may not be again forced into position, at least not without materially mutilating the packing.

It is an object of the invention to provide a pilot or holding member which may be employed as a part of the pump plunger while the pumping is being done, but which will remain in the well and hold the packing in position when the pump plunger is withdrawn, thus making it possible to again insert the plunger whenever desired.

It is a further object to provide a pilot member of the character described which is resilient in its action and wherein danger of injury to the pump and the pump plunger is reduced to a minimum. It is desired that the pilot member be adapted for use in connection with any type of packing within the pump barrel, and that it be simple and positive in its action and not liable to get out of order.

In the drawing, a preferred embodiment of the invention is disclosed. In Fig. 1 I have shown the pilot member in position within the pump barrel and shown as holding the packing in position and ready to receive the pump plunger, the parts being shown in central vertical section. Fig. 2 is a side elevation, partly in central section and parts being broken away, illustrating the formation of the pump plunger to co-operate with the pilot member. Figs. 3 and 4 show the upper and lower ends, respectively, of

the pump barrel and show the pump plunger in position for the pumping operation within the pump barrel, the parts being shown in central vertical section.

In illustrating the operation of my detachable pilot, I have shown a type of packed pump such as is disclosed in my prior application for Patent, No. 90,085, filed February 23rd, 1926. The pump tubing, indicated at 1, is connected to a pump barrel having packing members thereon arranged in stages or sections. This packing device is connected by a coupling 2 to the tubing. Said coupling 2 has its lower end threaded externally to receive the upper end 3 of the section 4. Said section 4 is a tubular nipple having a washer or ring 5, threaded therein adjacent the section 2 and having an opening to fit somewhat closely about the pump plunger 6 which reciprocates therein. The lower internal diameter of the section 4 is tapered downwardly at 7 to form a seat for a bushing or sleeve 8 which is cylindrical on its inner face and adapted to make a tight contact with the pump barrel 6, and tapered on its outer face to fit the seat 7. When in position in said seat it furnishes a packing member fitting in approximately fluid-tight relation about the pump plunger.

The upper end of the bushing 8 is provided with a downwardly tapered seat 9 which has a much more abrupt taper than that of the seat 7. In the seat 9 is a tapered slip 10 which is understood as being sectioned vertically and as having a guide ring 11 at the upper end, said ring having a series of radial downwardly projecting lugs thereon fitting within openings in the sections of the slip. This allows the sections of the slip to expand inwardly or outwardly relative to the ring but prevents their movement circumferentially on the ring. The ring 11 is held resiliently against the slip 10 by means of a spring 12 bearing at its upper end against the washer 5 and its lower end against said ring. It is contemplated that under ordinary circumstances the slips 10 will be held continually in close engagement with the pump plunger and serve to prevent any leakage whatever of fluid past them. It will not be until the packing 10 has been nearly worn out that the bushing 8 will tend to wear, said bushing acting to steady the ac-

tion of the pump plunger and holding it in exact alignment.

As many sections 4 or 4' may be employed in packing the pump barrel as is found necessary or desirable. I have shown two such sections, the lower section being secured to a coupling 13 which connects the same with the upper end of the pump barrel or tubing 14, which extends downwardly for connection with the usual standing valve and perforated pipe thereon.

To hold the packing expanded when the pump plunger is withdrawn, I have provided a detachable pilot 15, shown in Figs. 1 and 15 4. Said pilot member comprises a barrel or sleeve, the walls of which may be made comparatively thin. Its upper end is open and adapted to fit over the outer surface of an extension of the pump barrel. Its lower end 20 is threaded on its interior to engage with a tubular nut or stop member 16.

A resilient plunger locking sleeve 17 is fitted within the nut 16 and slidably closely therein. The outer end of the nut 16 has 25 opposite notches 18 therein to engage with a spanner wrench whereby the nut may be adjusted in its seat. The locking member 17 is a tubular member threaded at its lower end for engagement with a nut 19 of slightly 30 larger diameter than the guide member 15. When screwed in position on the lower end of the locking member, it is anchored in position by a set screw 20. The upper end 35 of the locking member above the nut 16 is slightly tapered at 21 and below said tapered surface is a radial lug or flange 22, the lower shoulder of which acts as a bearing for the upper end of a tension spring 23, the lower end of which bears against the 40 nut 16. It will thus be seen that the locking sleeve 17 is held resiliently within the lower end of the pilot member by the spring 23 and allows a downward movement of the 45 locking member relative to the pilot member against the tension of the said spring 23.

The lower end of the pump plunger is provided with an extension to engage and co-operate with the pilot member. Said extension is a tubular barrel threaded at its 50 upper end for engagement at 24 within the lower end of the plunger body 25. It extends downwardly from the plunger and is reduced in diameter toward the lower end, 55 and the said lower end is provided with upwardly extending slots 26; as many of said slots being provided as is necessary to allow the compression of the lower end of the barrel. At the extreme lower end the diameter of the barrel is again slightly enlarged to provide a tapered shoulder 27, the lower end of the barrel being also rounded and tapered at 28.

The pilot member 15 is provided, adjacent the upper end of the locking sleeve 21, with 60 an annular recess 29 of sufficient length to

receive and engage with the enlarged lower end 30 of the pump plunger extension, in the manner shown in Fig. 4.

In the operation of my device, the pump barrel together with the packing members 4 70 therein are assembled with the pilot member 15 in position therein, and it will be noted from the construction of this particular type of packing that the pilot member may be inserted from the lower end of the 75 packed pump barrel without difficulty, and it is contemplated that it will be inserted upwardly through the packing until the nut 19 at the lower end of the locking member comes in contact with the lower portion of 80 the packing or of the pump barrel. The parts will then be approximately in the position shown in Fig. 1.

The pump barrel may be then inserted into the well and thereafter the pump 85 plunger at the lower end of the usual sucker rod may be forced downwardly into the barrel and the lower end 30 of the pump barrel extension will be received within the upper end of the pilot member and may be slightly compressed and forced downwardly 90 therein until the lower end of the pump plunger extension contacts with the upper end of the locking sleeve 21. Said sleeve will be forced downwardly to some extent 95 against the tension of the spring 23 until the enlarged lower end 30 of the pump barrel extension is forced into the recess 29 in the pilot member. This will latch the pump plunger and the pilot member together, so 100 that thereafter the reciprocation of the pump plunger will also reciprocate the pilot member during the operation of the pump.

When it is desired to remove the pump 105 plunger, the said plunger is drawn upwardly until the nut 19 at the lower end of the pilot member engages with the lower end of the packing device, as shown in Fig. 1. An upward pull of the pump plunger thereafter 110 will draw the pilot member slightly upward 115 relative to the locking sleeve, and allow the pump plunger extension to be compressed by the upper shoulder of the recess 29 and allow the pump plunger to move away from the pilot sleeve, leaving the sleeve in the position shown in Fig. 1 and 120 allowing the plunger to be withdrawn without further difficulty. It will be noted that the pilot member is in a position holding the packing expanded so that there will be no 125 difficulty in introducing the pump plunger again in the manner set forth. This pilot, constructed to be automatically disengaged to hold the packing in position, is an important feature in all packed pumps, and it is to be understood that it is adapted to be used on a pump plunger in any type of 130 packed pump, that is, a pump having packing on the inner face of the pump barrel itself. It is capable of use upon pumps or

rods which have to be inserted within a packed sleeve, and I do not wish to be limited in the application of my invention to the particular form of construction shown in the drawing.

Having thus described my invention, what I claim as new and desire to protect by Letters Patent is:

1. In a device of the character described, a barrel, a cylindrical member movable therein, expansible packing means in said barrel bearing against said member, a pilot member on one end of said movable member, means holding said pilot member in resilient engagement with said movable member, said pilot holding means being adapted to be automatically disengaged, to retain said packing in position when said movable member is withdrawn therefrom.
2. In a device of the character described, a barrel, a cylindrical member movable therein, expansible packing means in said barrel bearing against said member, a tubular pilot member on one end of said movable member, means including a locking sleeve in the lower end of said pilot member, for holding said pilot member in resilient engagement with said movable member, said pilot holding means being adapted to be automatically disengaged, to retain said packing in position when said movable member is withdrawn therefrom.
3. In a reciprocating pump, a pump barrel, a plunger therein, a packing means in said pump barrel fitting about said plunger, a pilot member on said plunger, means holding said pilot member on said plunger, and means co-operating with the packing in said pump barrel to release said pilot member from said plunger, to retain said packing in position when said plunger is withdrawn.
4. In a reciprocating pump, a pump barrel, a plunger therein, a packing means in said pump barrel fitting about said plunger, a pilot member on said plunger, a locking sleeve acting to automatically lock said pilot member releasably to said plunger, and means co-operating with the packing in said pump barrel to release said pilot member from said plunger, to retain said packing in position when said plunger is withdrawn.
5. In a reciprocating pump, a pump barrel, a pump plunger therein, expansible packing means in said barrel fitting about said plunger, an extension at the lower end

of said plunger, a pilot sleeve on said extension, the lower end of said plunger being slightly enlarged to fit within a recess in said extension, means to hold said enlarged end of the plunger within said recess, said means being automatically releasable when said plunger is drawn upwardly out of said packing.

6. In a reciprocating pump, a pump barrel, a pump plunger therein, expansible packing means in said barrel fitting about said plunger, an extension at the lower end of said plunger, a pilot sleeve on said extension, the lower end of said plunger being slightly enlarged and slotted vertically to fit within a recess in said extension, means including a tapered sleeve fitting in the lower end of said plunger to hold said enlarged end of the plunger within said recess, said means being automatically releasable when said plunger is drawn upwardly out of said packing.

7. In a reciprocating pump, a pump barrel, a pump plunger therein, packing means between said pump barrel and said pump plunger, and a pilot sleeve detachably engaging the lower end of said plunger, and adapted to be automatically released from said pump plunger, when said plunger is drawn upwardly out of said packing.

8. In a reciprocating pump, a pump barrel, a pump plunger therein, packing means between said pump barrel and said pump plunger, and a pilot sleeve detachably engaging the lower end of said plunger including a locking sleeve fitting within the lower end of said guide sleeve and said plunger and adapted to be automatically released with said pilot sleeve from said pump plunger, when said plunger is drawn upwardly out of said packing.

9. In a reciprocating pump including a pump barrel, a pump plunger, and a packing means on said pump barrel fitting about said pump plunger; the combination of a pilot sleeve detachably engaging the said pump plunger and adapted to contact with said pump barrel to be released automatically when said plunger is withdrawn, to retain said packing in position, in the manner described.

In testimony whereof I hereunto affix my signature this 21st day of June, A. D. 1926.

GERALD R. LIVERGOOD.
